UNITED STATES PATENT OFFICE.

WILLIAM H. IVERS, OF DEDHAM, ASSIGNOR TO THE IVERS & POND PIANO CO., OF BOSTON, MASSACHUSETTS.

DAMPER FOR PIANOS.

SPECIFICATION forming part of Letters Patent No. 392,270, dated November 6, 1882.

Application filed August 22, 1882. Serial No. 253,453. (No model.)

To all whom it may concern:

Be it known that I, WILLIAM H. IVERS, a citizen of the United States, residing at Dedham, in the county of Norfolk and State of Massachusetts, have invented certain new and useful Improvements in Dampers for Pianos; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to an attachment for pianos, termed a "damper." The object of said dampers is to deaden or lessen the volume of the tone of the instrument to such a degree as to render the tones inaudible at a short distance, and thereby prevent wear of the hammers, as also the annoyance to others in the vicinity, which would ordinarily result from continuous practicing when such a device is not employed.

20 25 My invention relates not only to improvements in the construction of a damper-bar by which it is rendered adjustable to obviate any sag or deviation from the horizontal, but, further, in the mode of mounting it, whereby the same may be readily removed, if so desired.

The drawings represent, in Figure 1, a plan of a damper applied to a piano; Fig. 2, a front elevation; Fig. 3, a cross-section of the same. Fig. 4 is a cross-section showing the relations 30 of the strings and damper and the mode of operating the latter.

In said drawings, 2 2 represent the ends of an upright piano, for which this damper is more especially adapted. The bass strings are shown at 3, the treble at 4, the bridge at 5, and hammers at 6.

This damper belongs to that class which ordinarily have been composed of a bar of wood, to which has been secured an apron of felt or analogous material. This damper-bar operates to carry the apron into the path of the hammers and interpose it between the latter and the strings. No direct contact of the hammers with the strings occurs, but the vibrations of the strings are simply lessened in quantity or deadened in contradistinction to

that class termed "mute-bar dampers," wherein the weight of the damper almost, if not quite entirely, stops the vibrations.

This invention, in substance, consists in the manner of constructing the damper shown at 7. This is composed, primarily, of a long bar, 8, which extends the entire length of the instrument, pivotally mounted, as hereinafter described. Preferably this bar is of wood or similar material, for convenience in securing the apron 9, so called, thereto, which is generally fastened to the bar by glue or other adhesive compound, and hangs vertically therefrom. To prevent this rod from sagging, or to remedy any twist or departure from a straight line, I have secured and longitudinally aligned along said damper-bar a series of screw-eyes, 10. Through these eyes are passed a metallic rod, 12, preferably tubular. Thus the inherent stiffness of the metal serves to prevent any sag or deviation from the horizontal of the wooden bar 8, with its pendent apron, while if any adjustment is required the rod is removed, the screw-eye at the spot to be adjusted is set in or out, when the rod is replaced. The bar 8 is thus drawn inwardly or thrust outwardly, according to the movement of the screw eye or eyes, which may have been changed to produce such adjustment.

To render the above device operative or inoperative, the ends of the metallic rod are secured upon the upper free ends of twin rocker-arms 13, affixed on pins 14, one in each end 2 of the piano-case. The lower extremity 85 of one of said rocker-arms is secured to an actuating push-rod, 15, furnished with a knob and operating after the manner of organ-stops, sliding horizontally through a bearing-block, also upon the end of the piano. Thus in the event of removal of the damper 7 the pivoted pins 14 14 are withdrawn, when the entire attachment may be lifted out.

In Fig. 1 it will be seen that the bar 8 is cut away in that portion 16 adjacent to the bass-strings, in order to bring the apron equidistant from both sets of strings 3 3, 4 4, and thereby render the function of the damper the same at all points and muffle the tones equally.

It will be seen that if the push-bar 15 be thrust inwardly the damper 7 will be rendered inoperative, while a pull outwardly will rock

the arms 13 and cause the apron to drop and intervene between the hammers and their co-operating strings, lessening the amount of tone and saving wear of the hammers by striking the strings. No weight is brought upon the latter, and they are free to vibrate. Such vibrations are, however, very slight, since the force of the hammers is almost entirely stopped by the intervention of the apron. With this style of damper the tones are merely modified in strength, thus giving the performer the advantage of hearing the musical consonance of the strings, which is of great advantage in playing. This is not accomplished in a mute-bar damper, where the weight of the latter checks the vibrations.

It is to be understood that this damper is to be used independently of the ordinary loud and soft pedal attachments, both of which can be used with effect in connection with this.

What I desire to claim is—

1. A damper for pianos, composed of a wooden bar, a metallic rod aligned thereabove, a series of screw-eyes by which the wooden bar is adjustably connected with and supported

by said rod, and a pendent apron secured to said bar, the entirety adapted to be operated to cause the apron to be interposed between the strings and the hammers, substantially as herein described.

30

2. A movable damper composed of a bar 8, its adjusting-screws 10, the flexible apron 9, and the rod 12, by which it is supported, combined with the rocker-arms 13 13, pivoted in the piano-ease, and their actuating push-rod 35 15, substantially as specified.

3. The combination, with the rocker-arms 13, their actuating push-rod 15, and the metallic rod 12, of the damper-bar 8, cut away at 16, adjacent to the strings 3 3, its adjusting screw-eyes 10, and the flexible pendent apron 9, all for purposes herein set forth and described.

40

In testimony whereof I affix my signature in presence of two witnesses.

WILLIAM H. IVERS.
